BOTTLE WITH AUTOMATIC ORIENTING HANDLE ASSEMBLY

BACKGROUND

1. Field of Art

The disclosure relates to a drinking bottle, more specifically to a drinking bottle with a handle assembly that automatically orients itself relative to a lid when the lid is assembled.

2. Description of the Related Art

Bottles with handles are often used by babies or children. Although attempts have been made to shape bottles for easier handling by babies or children, they generally lack the power or dexterity to adequately hold the bottles without assistive structures. Handles are often provided as such assistive structures so that babies or children may grab these handles without dropping the bottles. These handles may be attached to a ring that is inserted into the outer periphery of the body of the bottle so that the handles may be removed from the container for cleaning purposes. As the handles are reattached to the body of the bottle, their orientation may change or shift. In a bottle with an asymmetric top structure where a spout or a straw is shifted away from its axial center (e.g., towards the front of the bottle), such change or shift in the orientation of the handles may require manual readjustment so that the handles are appropriately oriented for handling by the babies or children.

SUMMARY

Embodiments relate to a drinking bottle that automatically orients handles in a predetermined direction when assembled. The drinking bottle includes a container, a handle assembly, and a lid. The container includes an open top, a first portion having a first outer dimension, and a second portion having a second outer dimension larger than the first dimension. The second portion is further away from the open top than the first portion. The handle assembly includes a ring that slidably engages the second portion and receives the first portion. The ring includes a first protrusion extending away from the second portion, and at least one handle is attached to the ring. The lid engages the handle assembly. The lid has an inner shape dimensioned to receive the first portion but not the second portion. The lid is formed with a first notch corresponding to the first protrusion to receive and engage the first protrusion for rotation of the lid with rotation of the handle assembly.

In one or more embodiments, an inner dimension of the ring is larger than the first outer dimension but smaller than the second outer dimension.

In one or more embodiments, the lid is secured to the container with the ring between the lid and the second portion by rotating the lid relative to the container.

In one or more embodiments, the first portion includes a first screw and the lid includes a second screw that engages with the first screw.

In one or more embodiments, the lid includes a second protrusion and the ring includes a second notch that receives and engages the second protrusion. The second protrusion pushes the second notch and rotates the ring to release the ring and the lid from the container.

In one or more embodiments, the internal surface of the ring is smooth.

In one or more embodiments, the ring includes a second protrusion at an opposite side of the first protrusion, and the lid includes a second notch that corresponds to the second protrusion at an opposite side of the first protrusion.

5 In one or more embodiments, the drinking bottle further includes an insert that engages and is assembled into a cavity in the lid. The insert is made of resilient material to provide sealing between the open top and the lid.

In one or more embodiments, the insert includes a top portion, a middle portion and a bottom portion. The top portion has an outer surface that is reverse tapered. The outer surface of the top portion engages and rests on a forward tapered inner surface of the cavity in the lid. The middle portion is attached to the top portion and has an outer surface that is forward tapered. The bottom portion is attached to the middle portion. The edges of the bottom portion are captured between an inner annular rib of the lid and the open top of the container.

10 In one or more embodiments, the drinking bottle further includes a lid cover hinged to the lid. At least a part of the insert is compressed between the lid and the lid cover when the lid cover is closed.

15 In one or more embodiments, the drinking bottle further includes a lever attached to the lid. The lever locks the lid cover in a first position and the lever releases the lid cover in a second position. The lid cover is rotated away from the lid by a compressive force of the insert when the lever is placed in the second position.

20 In one or more embodiments, the lever includes a pair of latches for securing the lever to the lid.

25 In one or more embodiments, the insert applies biasing force to the lever to maintain the lever in the first position when external force is not applied to the lever.

30 In one or more embodiments, the insert includes a straw or a spout for accessing content in the container. The lid cover includes a housing that folds and receives or compresses the straw or the spout when the lid cover is closed.

35 In one or more embodiments, the straw or the spout applies a force to the lid cover that opens the lid cover.

40 In one or more embodiments, the lid includes a protrusion that is compressed by the lid cover when the lid cover is closed. The protrusion applies an opening force to the lid cover when the lever is placed in the second position.

45 Embodiments also relate to a drinking bottle that includes a container, a handle assembly and a lid. The handle assembly is rotatable relative to the container. The handle assembly includes a first pair of protrusion and notch. The lid engages the handle assembly and has a second pair of protrusion and notch that is inverse in shape relative to the first pair. The second pair mates with the first pair so that the handle assembly is rotated with a rotation of the lid. The first pair and the second pair are locked into position as the handle assembly and the lid are rotated onto the container.

50 In one or more embodiments, the lid screws onto the container with the handle assembly between the lid and the container. The distance between the first pair and the second pair in a longitudinal direction of the container is gradually reduced as the lid is screwed onto the container.

55 In one or more embodiments, an inner surface of the lid includes a first screw and an outer surface of the container includes a second screw that mates with the first screw.

60 In one or more embodiments, the first pair of protrusion and notch has an outer profile of a wave shape, and the second pair of protrusion and notch has an outer profile that is an inverse wave shape.

65 In one or more embodiment, the handle assembly further includes a third pair of protrusion and notch at a location of

the handle assembly radially opposite to the first pair, and the lid further includes a fourth pair of protrusion and notch at a location of the lid radially opposite to the second pair.

In one or more embodiments, the handle assembly includes a bottom surface that is rotatably about the container, and a top surface that contacts the lid when the lid and the handle assembly are screwed onto the container. The first pair is formed as part of the top surface.

BRIEF DESCRIPTION OF THE DRAWINGS

FIG. 1 is a perspective view of a drinking bottle with a lid cover closed, according to one embodiment.

FIG. 2 is a perspective view of the drinking bottle with the lid cover opened, according to one embodiment.

FIG. 3 is an exploded view of the drinking bottle, according to one embodiment.

FIG. 4 is a perspective view of a handle assembly, according to one embodiment.

FIGS. 5A and 5B are perspective views of a lid of the drinking bottle, according to one embodiment.

FIG. 6 is a perspective view of a lid cover of the drinking bottle, according to one embodiment.

FIGS. 7A and 7B are perspective views of a lever of the drinking bottle, according to one embodiment.

FIG. 8 is a perspective view of an insert, according to one embodiment.

FIGS. 9 and 10 are cross-sectional view of the drinking bottle, according to one embodiment.

FIGS. 11A through 11D are diagrams illustrating operations of screwing the lid onto or unscrewing the lid from a container, according to one embodiment.

FIGS. 12A through 12D are diagrams illustrating opening of the lid cover by the compressive force of the straw or a spout, according to one embodiment.

FIG. 13A through 13D are diagrams illustrating various shapes of notches and protrusions, according to various embodiments.

DETAILED DESCRIPTION OF EMBODIMENTS

Embodiments are described herein with reference to the accompanying drawings. Principles disclosed herein may, however, be embodied in many different forms and should not be construed as being limited to the embodiments set forth herein. In the description, details of well-known features and techniques may be omitted to avoid unnecessarily obscuring the features of the embodiments. In the drawings, like reference numerals in the drawings denote like elements. The shape, size and regions, and the like, of the drawing may be exaggerated for clarity.

Embodiments relate to a self-orienting handle assembly that is oriented in a predetermined direction relative to a lid when the lid is screwed onto a container. The handle assembly includes a locking structure that locks onto a counterpart locking structure of the lid as the lid is screwed onto the container. The locking structure may include at least one of a protrusion or a notch, and the counterpart locking structure may have an inverse shape. When the lid is screwed onto the container, the locking structure engages the counterpart locking structure and causes the handle assembly to rotate with the lid. When the lid is screwed onto the container, the locking structure locks onto the counterpart locking structure, and thereby prevents the handle assembly from rotating relative to the lid.

FIG. 1 is a perspective view of a drinking bottle 100 with a lid cover 110 closed, according to one embodiment.

Drinking bottle 100 includes a container 120 and other parts assembled onto container 120. In the embodiment of FIG. 1, drinking bottle 100 is of a cylindrical shape but drinking bottle 100 may be of various other shapes.

Parts that are assembled onto drinking bottle 100 may include, among other components, handle assembly 118 and lid 128. Handle assembly 118 and lid 128 are screwed onto drinking bottle 100 with a predetermined relationship due to locking structures. That is, when handle assembly 118 and lid 128 are assembled onto drinking bottle 100 by screwing lid 128 onto drinking bottle 100, handle 338 of lid 128 are oriented in a direction that is perpendicular to a direction in which straw 322 or spout 1208 is shifted relative to the center axis of container 120.

FIG. 2 is a perspective view of drinking bottle 100 with lid cover 110 opened to reveal insert 204, according to one embodiment. Lid cover 110 are coupled to lid 128 via hinges 502 in a rotatable manner between a first state (e.g., closed state, as shown in FIG. 1) and a second state (e.g., open state as shown in FIG. 2). When in the open state, insert 204 is revealed and accessible to the user of drinking bottle 100. The switch to the open state may be facilitated by protrusion 208 formed on the top surface of lid 128 as well as the compressive force applied by straw 322 or spout 1208, as described below in detail with reference to FIGS. 12A through 12D.

When in use, a user holds one or both of handle 338A, handle 338B, and accesses straw 322 or spout 1208 that is part of insert 204. In the closed state, a lever 114 engages lid cover 110. In the open state, lever 114 releases lid cover 110 and enables lid cover 110 to rotate away as shown in FIG. 2.

FIG. 3 is an exploded view of drinking bottle 100, according to one embodiment. Drinking bottle 100 may include, among other components, lid cover 110, lid 128, insert 204, handle assembly 118 and container 120. In other embodiments, drinking bottle 100 may include additional components not illustrated in FIG. 3. Alternatively, some components illustrated in FIG. 3 may be omitted (e.g., lid cover 110). Further, modifications may be made on how the components are assembled (e.g., insert 204 may be assembled from a top surface of lid 128 instead of being assembled via the bottom of lid 128).

Lid 128 generally has side surfaces 308, 310 and is assembled on top of container 120. Side surface 308 is dome shaped while side surface 310 is cylindrically shaped. Lid 128 is formed with cavity 540 in which insert 204 may be installed. Bottom surface 320 of lid 128 contacts top surface 358 of handle assembly 118. Bottom surface 320 has notches 314A, 314B and protrusions 318A, 318B that engage with protrusions 332A, 332B and notches 334A, 334B of handle assembly 118 so that handle assembly 118 rotates with lid 128 when screwing lid 128 onto container 120 or when unscrewing lid 128 from container 120. The details of lid 128 are described below with reference to FIGS. 5A and 5B.

Lever 114 is assembled onto lid 128 so that it may pivot relative to lid 128. When pressed in, lever 114 disengages lid cover 110 and enables lid cover 110 to rotate into the open state. When lid cover 110 is pressed down towards lid 128, lever 114 engages lid cover 110 and locks lid cover 110 in the closed state. Biasing force is applied to lever 114 by insert 204 so that lever 114 returns to a locking position and remains in the position when external force (e.g., by the user pressing the lever 114) is not applied to lever 114. The details of lever 114 are described below with reference to FIGS. 7A and 7B.

Insert 204 is removably attached to lid 128 and also assists sealing of open top 356 of container 120 in conjunction with lid 128. Insert 204 is made of resilient materials and may be formed with straw 322 or spout 1208. For example, insert 204 may be made of silicone, thermoplastic elastomers, rubber or latex. By removably attaching insert 204 to lid 128, cleaning of insert 204 and lid 128 may be facilitated, and replacement of insert 204 may be performed easily when it becomes worn or damaged due to repeated use. Insert 204 includes, among other components, top portion 326, middle portion 328 and bottom portion 330. Top portion 326 contacts and is supported by a forward tapered side surface 510 of lid 128 when insert 204 is assembled onto lid 128. The details of insert 204 are described below with reference to FIG. 8.

Handle assembly 118 includes ring 340 onto which handles 338A, 338B are attached. Ring 340 includes top surface 358 and bottom surface 342. In one or more embodiments, ring 340 has a bottom surface 342 that contacts step 350 of container 120 in a rotatable manner. On the other hand, handle 338 contacts bottom surface 320 of lid 128 and includes protrusions 332A, 332B and notches 334A, 334B for rotation of handle assembly 118 during screwing or unscrewing of lid 128. Handles 338A, 338B are grasped by the user during the use of drinking bottle 100. In one or more embodiments, each pair of protrusions/notches 332A, 334A, and 332B, 334B has a wave pattern.

Container 120 has first portion 352 and second portion 348 connected to first portion 352. First portion 352 has an outer diameter smaller than second portion 348, and has screw 344 formed on its outer surface. The outer diameter of first portion 352 is sufficiently small so that ring 340 of handle assembly 118 may slide onto it but the outer diameter of second portion 348 is sufficiently large so that ring 340 does not slide over it. First portion 352 and second portion 348 are separated by step 350 that contacts bottom surface 342 of handle assembly 118 in a rotatable manner. First portion 352 also has open top 356 that is sealed by insert 204, as described below in detail with reference to FIGS. 9 and 10. Although second portion 348 is illustrated in FIG. 3 as having a symmetric cylindrical shape, second portion 348 may have various other shapes as long as step 350 is circular shaped. Container 120 may have a bottom shape that enables container 120 to stay upright when placed on a flat surface.

In order to assemble drinking bottle 100, lever 114 and lid cover 110 are assembled onto lid 128. Insert 204 is then inserted from the bottom of lid 128 so that top portion 326 rests on an inner surface 510 of lid 128. Ring 340 of handle assembly 118 is then inserted onto first portion 352 of container 120 so that bottom surface 342 rests on step 350. Finally, lid 128 is screwed onto screw 344 of container 120.

As lid 128 is screwed onto screw 344, lid 128 moves downward along a longitudinal direction 380, notch 314A and protrusion 318A align with protrusion 332A and notch 334A while notch 314B and protrusion 318B align with protrusion 332B and notch 334B so that handle assembly 118 rotates with lid 128, as described below in detail with reference to FIGS. 11A and 11B. In order to disassemble drinking bottle 100, a process is taken in an order reverse to the assembling process.

FIG. 4 is a perspective view of handle assembly 118, according to one embodiment. Handle assembly 118 may include, among other components, ring 340 and handles 338A, 338B placed at radially opposite sides of ring 340. Ring 340 has an inner surface 408 that is smooth and faces the first portion 352 of container 120 and an outer surface on which handles 338A, 338B are attached. Pairs of notches

334A, 334B are formed on top surface 358 at locations 90 degrees apart from handles 338A, 338B. In one or more embodiments, handles 338A, 338B extend away from ring 340 and then are curved downwards. The shape of handles in FIG. 4 is merely illustrative and handles may take various other shapes instead.

FIGS. 5A and 5B are perspective views of lid 128, according to one embodiment. Lid 128 has hinges 502 at its back and structures for securing lever 114 at its front. Hinges 502 have holes 124 formed in a horizontal direction to receive pins 602 of lid cover 110 in a rotatable manner. Lid 128 has a top surface 530 and side surface 308 extending downwards from top surface 530.

Part of top surface 530 and side surface 308 are cut away to form cavity 534 for receiving lever 114 and cavity 540 for receiving insert 204. Top surface 530 and side surface 308 also have rests 506A, 506B and latches 522. Each of rests 506A, 506B are shaped as a flat plate, and are inserted into corresponding spaces 732 of lever 114. After lever 114 is assembled onto lid 128, rests 506A, 506B enable lever 114 to slide vertically while restricting a vertical movement of lever 114. Indents 520 are formed between latches 522 and an inner surface of lid 128 to receive bottom portion 330 of insert 204 so that bottom portion 330 provides sealing between lever 114 and lid 128.

The inner surface of lid 128 is also formed with screw 508 to mate with screw 344 of container 120. In some embodiments, top surface 530 is also provided with protrusion 208 that may provide compressive force to open lid cover 110 when lever 114 is pressed. Bottom surface 320 of lid 128 has pairs of notches 314 and protrusions 318 at locations corresponding to those of protrusions 332 and notches 334 of handle assembly 118. Frustoconical surface 572 is provided at the upper part of the inner surface of lid 128. Latches 708 of lever 114 are locked onto frustoconical surface 572 when lever 114 is assembled onto lid 128.

FIG. 6 is a perspective view of lid cover 110, according to one embodiment. Lid cover 110 may include flat portion 302 and housing 304 extending upward from flat portion 302. End portion 604 extends backward from flat portion 302 and is formed with pins 602 for attaching to lid 128 in a rotatable manner.

At a bottom edge of housing 304, rib 610 is formed to latch onto groove 702 of lever 114 in the closed state. When lever 114 is pressed, rib 610 is released from groove 702 and enables lid cover 110 to rotate about pins 602 into the open state. Housing 304 has an internal space that can compress or fold and receive straw 322 or spout 1208 in the closed state. The compression or folding of straw 322 or spout 1208 in housing 304 provides force to open lid cover 110 in a popping manner, as described below in detail with reference to FIGS. 12A through 12D. Further, folding of straw 322 further advantageously prevents contents in container 120 from leaking out through the straw 122 when the lid cover 110 is closed.

FIGS. 7A and 7B are perspective views of lever 114, according to one embodiment. Lever 114 includes front plate 704 that is formed with groove 702. When front plate 704 is pressed, latches 708 of lever 114 slides horizontally relative to rests 506A, 506B while the vertical movement of lever 114 is restricted by rests 506A, 506B. In this way, lid 128 releases rib 610 of lid cover 110, which pops open lid cover 110. When closing lid cover 110, rib 610 of lid cover 110 slides down an upper portion of front plate 704 and is received in groove 702 in a latching manner. Latches 708 extend backward symmetrically at a rear side of lever 114.

By pressing latches 708 inwards, lever 114 may be disassembled from lid 128. Lever 114 also includes horizontal rib 722 and vertical rib 712 at its back to provide rigidity and strength to lever 114. Further, horizontal rib 722 contacts top portion 326 of insert 204 while vertical rib 712 contacts middle portion 328 of insert 204 so that insert 204 applies biasing force to lever 114. The structure of lever 114 in FIGS. 7A and 7B is merely illustrative, and various modifications may be made to lever 114. For example, lever 114 may have a different exterior shape, have more ribs than what is shown in FIG. 7B, and mechanisms other than latches 708 may be used for attaching to lid 128.

Lever 114 is pressed by insert 204 so that lever 114 is biased into a position where groove 702 is shifted forward by insert 204. Because insert 204 is made of resilient material, insert 204 may provide biasing force to lever 114 so that groove 702 of lever 114 remains and is biased into a position that locks rib 610 of lid cover 110 in a closed state when lever 114 is not pressed by the user. For this purpose, lever 114 has vertical rib 712 that contacts middle portion 328 of insert 204, and a horizontal rib 722 that contact top portion 326 of insert 204.

Because insert 204 provides the biasing force to insert 204, no separate biasing mechanism such as spring is used to push lever 114 into the locking position. Such use of insert 204 as a biasing mechanism beneficially reduces the number of parts and complexity of the assembly.

FIG. 8 is a perspective view of insert 204, according to one embodiment. In the embodiment of FIG. 8, straw 322 extends from top surface 810. In other embodiments, other structures (e.g., spout 1208) may extend from top surface 810. Slanted surface 804 extends in a forward tapered manner from top surface 810 and rests on an inner surface 510 of lid 128 when insert 204 is assembled onto lid 128. Air vent 802 is formed on top surface 810 to enable liquid in container 120 to flow out of straw 322 (or spout 1208) despite open top 356 being sealed by insert 204 and lid 128. Insert 204 includes bottom portion 330 with upper surface, top portion 326, and middle portion 328 between bottom portion 330 and top portion 326. Top portion 326 is reverse tapered.

Insert 204 is pushed upward from the bottom of lid 128 for mounting onto lid 128. The top part of top portion 326 has a large dimension than that of cavity 540. By supplying sufficient upward force, top portion 326 deforms and snaps into cavity 540. After inserting top portion 326 into cavity 540, the side surface that is reverse tapered rests on inner surface 510 of lid 128 and restricts a downward movement of insert 204. The upward movement of insert is also restricted by middle portion 328 that has a larger dimension than that of cavity 540. The side surface of middle portion 328 is forward tapered.

FIGS. 9 and 10 are cross-sectional views of drinking bottle 100, according to one embodiment. When lid cover 110 is closed, straw 322 is compressed or folded and received in interior space of housing 304 of lid cover 110. This provides compressive force to open lid cover 110 when lever 114 is pressed and rib 610 is released from groove 702.

Bottom portion 330 of insert 204 is compressed between inner annular rib 924 that is formed at the bottom of lid 128 and open top 356 of container 120. Bottom portion 330 is made of resilient material, and hence, bottom portion 330 seals open top 356 when lid 128 is screwed onto container 120 so that the liquid in container 120 is not leaked.

Vertical rib 712 of lever 114 presses down and deforms bottom portion 330 when lever 114 is installed onto lid 128. Since bottom portion 330 is made of resilient material and

is deformed, it provides elastic force to push lever 114 towards the left in FIG. 9. Accordingly, bottom portion 330 pushes vertical rib 712 by a predetermined amount of force that must be overcome by the user to release lid cover 110. 5 By biasing lever 114 with the predetermined amount of force, inadvertent or accidental opening of lid cover 110 may be prevented.

FIGS. 11A and 11B are diagrams illustrating the operations of lid 128 and handle assembly 118 during screwing of lid 128 onto container 120, according to one embodiment. As shown in FIG. 11A, when lid 128 is rotated to move the illustrated portion of lid 128 in direction Da, pairs of 10 protrusion and notch at lid 128 and protrusion 318 make contact at point 1102. Hence, protrusion 318 pushes protrusions 332 and causes handle assembly 118 to rotate along with notch 314.

As lid 128 is rotated, lid 128 moves downward as in direction Db as shown in FIG. 11B until gap Ga between lid 20 128 and handle assembly 118 is substantially zero. After gap 25 Ga become substantially zero, lid 128 is fully screwed onto container 120 and no further rotation may be made in the direction indicated by direction Da. In this way, lid 128 and handle assembly 118 are always positioned at certain relative angles when lid 128 are screwed onto container 120.

Because straw 322 or spout 1208 is offset towards the front of lid 128 and handle 338 are located 90 degrees apart from the pairs of protrusion and indents on ring 340, protrusion 332 or spout 1208 is always biased in a direction 30 90 degrees rotated from handle 338. This enables the user to conveniently grasp handle 338 with protrusion 332 or spout 1208 offset toward the user's mouth for convenient consumption of liquid in container 120.

FIGS. 11C and 11D are diagrams illustrating the operation 35 of lid 128 and handle assembly 118 during unscrewing of lid 128 from container 120, according to one embodiment. When lid 128 is rotated so that a portion of lid 128 shown in FIG. 11C moves in direction Dd, protrusion 332 of handle assembly 118 contacts notch 314 of lid 128 at point 1104, and notch 334 of handle assembly 118 contacts protrusion 318 of lid 128 at point 1108 to rotate handle assembly 118 in direction Dd. As lid 128 is rotated, lid 128 moves in direction Dc until gap Ga between lid 128 and handle assembly 118 are sufficiently large so that protrusion 318 and protrusion 332 no longer make contact at any points on notch 314 and notch 334, respectively, as shown in FIG. 11D. 40 Then, lid 128 may be fully unscrewed from container 120 without rotating handle assembly 118.

FIGS. 12A and 12B are diagrams illustrating opening of 50 lid cover 110 by the compressive force of folded straw 322, according to one embodiment. When lid cover 110 is closed, straw 322 is compressed or folded within interior space of housing 304. The compressed/folded straw 322, hence, exerts a force on the bottom of housing 304 so that lid cover 55 110 pops up and rotates about holes 124 when front plate 704 is pressed. In one or more embodiments, such force may be increased by providing protrusion 208 on the top surface of lid 128.

FIGS. 12C and 12D are substantially identical to FIGS. 60 12A and 12B, except that spout 1208 is provided on insert 204 instead of straw 322. In the embodiments of FIGS. 12C and 12D, spout 1208 is compressed by housing 304 when lid cover 110 is closed, and therefore, exerts a force on the bottom of housing 304 so that lid cover 110 pops open when 65 front plate 704 is pressed. Insert 204 may be provided with various other mechanisms for consuming liquid in drinking bottle 100, other than straw 322 and spout 1208.

Although above embodiments are described with reference to two pairs of curved protrusions and notches with inverse shapes in lid 128 and handle assembly 118, protrusions and notches with straight lines, zigzagged shapes, or other configurations may also be used. Some example shapes of protrusions and corresponding shapes of notches are illustrated in FIGS. 13A through 13D.

Although the present disclosure has been described above with respect to several embodiments, various modifications can be made within the scope of the disclosure. Accordingly, the disclosure described above is intended to be illustrative, but not limiting.

What is claimed is:

1. A drinking bottle, comprising:

a container comprising:

an open top,

a first portion having a first outer dimension, and a second portion having a second outer dimension larger than the first outer dimension, the second portion being further away from the open top than the first portion;

a handle assembly comprising:

a ring configured to slidably engage the second portion and receive the first portion, the ring comprising a topmost surface facing away from the second portion and farthest from the second portion, a bottom surface facing toward the second portion, and an internal surface connecting the topmost surface and the bottom surface, a first protrusion formed along the topmost surface to extend away from the second portion, and

at least one handle attached to the ring; and

a lid configured to engage the handle assembly, the lid having an inner shape dimensioned to receive the first portion but not the second portion, the lid formed with a first notch corresponding to the first protrusion to receive and engage the first protrusion for rotation of the lid with rotation of the handle assembly.

2. The drinking bottle of claim 1, wherein an inner dimension of the ring is larger than the first outer dimension but smaller than the second outer dimension.

3. The drinking bottle of claim 1, wherein the lid is secured to the container with the ring between the lid and the second portion by rotating the lid relative to the container.

4. The drinking bottle of claim 3, wherein the first portion comprises a first screw and the lid comprises a second screw that engages with the first screw.

5. The drinking bottle of claim 4, wherein the lid comprises a second protrusion adjacent to the first notch, and the ring comprises a second notch adjacent to the first protrusion, the second notch configured to receive and engage the second protrusion, the second protrusion configured to push the second notch and rotate the ring to release the ring and the lid from the container.

6. The drinking bottle of claim 4, wherein the internal surface of the ring is smooth.

7. The drinking bottle of claim 1, wherein the ring comprises a second protrusion at an opposite side of the first protrusion, and the lid comprises a second notch that corresponds to the second protrusion at an opposite side of the first protrusion.

8. The drinking bottle of claim 1, further comprising an insert configured to engage and assemble into a cavity in the lid, the insert made of resilient material to provide sealing between the open top and the lid.

9. The drinking bottle of claim 8, wherein the insert comprises:

a top portion having an outer surface that is reverse tapered, the outer surface of the top portion engaging and resting on a forward tapered inner surface of the cavity in the lid,

a middle portion attached to the top portion and having an outer surface that is forward tapered, and

a bottom portion attached to the middle portion, wherein edges of the bottom portion are captured between an inner annular rib of the lid and the open top of the container.

10. The drinking bottle of claim 8, further comprising a lid cover hinged to the lid, at least a part of the insert being compressed between the lid and the lid cover when the lid cover is closed.

11. The drinking bottle of claim 10, further comprising a lever attached to the lid, the lever configured to lock the lid cover in a first position and the lever being configured to release the lid cover in a second position, wherein the lid cover is rotated away from the lid by a compressive force of the insert when the lever is placed in the second position.

12. The drinking bottle of claim 11, wherein the lever comprises a pair of latches for securing the lever to the lid.

13. The drinking bottle of claim 11, wherein the insert applies a biasing force to the lever to maintain the lever in the first position when external force is not applied to the lever.

14. The drinking bottle of claim 11, wherein the lid comprises a protrusion that is configured to be compressed by the lid cover when the lid cover is closed, the protrusion being configured to apply an opening force to the lid cover when the lever is placed in the second position.

15. The drinking bottle of claim 10, wherein the insert comprises a straw or a spout for accessing content in the container, and the lid cover comprises a housing configured to fold or compress and receive the straw or the spout when the lid cover is closed.

16. The drinking bottle of claim 15, wherein the straw or the spout applies a compressive force that opens the lid cover.

17. A drinking bottle, comprising:

a container;

a handle assembly rotatable relative to the container, the handle assembly comprising a first pairing of a first protrusion and a first notch along a topmost surface of the handle assembly that is perpendicular to an internal surface of the handle assembly that faces the container; and

a lid configured to engage the topmost surface of the handle assembly, the lid having a second pairing of a second protrusion and a second notch along a bottom surface of the lid, the second pair of protrusion and notch having a shape that is complementary to the first pairing, the second pairing being configured to mate with the first pair so that the handle assembly is rotated with a rotation of the lid,

wherein the first pairing and the second pairing are configured to lock into position as the handle assembly and the lid are rotated onto the container.

18. The drinking bottle of claim 17, wherein the lid is configured to screw onto the container with the handle assembly between the lid and the container, and wherein a distance between the first pairing and the second pairing in a longitudinal direction of the container is gradually reduced as the lid is screwed onto the container.

19. The drinking bottle of claim **18**, where an inner surface of the lid comprises a first screw and an outer surface of the container comprises a second screw that mates with the first screw.

20. The drinking bottle of claim **17**, wherein the first notch is adjacent to the first protrusion to form a wave shape on the topmost surface of the handle assembly with the first protrusion. 5

21. The drinking bottle of claim **17**, wherein the handle assembly further comprises a third pairing of a third protrusion and a third notch at a location of the handle assembly diametrically opposite to the first pairing, and the lid further comprises a fourth pairing of a fourth protrusion and a fourth notch at a location of the lid radially opposite to the second pairing. 10

22. The drinking bottle of claim **17**, wherein the handle assembly comprises a bottom surface that is rotatable about the container. 15

23. The drinking bottle of claim **17**, further comprising: an insert of resilient material and configured to engage 20 and assemble onto the lid, and a lever attached to the lid, the lever configured to lock a lid cover in a first position and the lever being configured to release the lid cover in a second position, the lever configured to receive biasing force from the insert 25 to maintain the lever in the first position when external force is not applied to the lever.
